UNITED STATES PATENT OFFICE.

FREDERICK M. LANDON, OF TACOMA, WASHINGTON.

WRENCH.

1,109,766.

Specification of Letters Patent.

Patented Sept. 8, 1914.

Application filed July 8, 1912. Serial No. 708,148.

To all whom it may concern:

Be it known that I, FREDERICK M. LANDON, a citizen of the United States, and resident of Tacoma, in the county of Pierce and 5 State of Washington, have invented certain new and useful Improvements in Wrenches, of which the following is a specification.

This invention relates to wrenches and especially to those wrenches which are adapted to grip a pipe, a shaft, or other cylindrical object, and has for its objects to provide a wrench which will grip the pipe in three or more places; which cannot accidentally be removed from the pipe; which may be 10 worked when there is but little space back of the pipe; and in which the strains are so distributed that it will be very strong, though light, and will be very durable. I attain these and other objects by the devices, 15 mechanisms, and arrangements illustrated in the accompanying drawings in which—

Figure 1 is a side elevation of the wrench showing it as engaging a pipe; Fig. 2 is a similar view of the head of the wrench showing 20 it being placed in position to engage a pipe; Fig. 3 is a similar view showing a modified form of jaw; Fig. 4 is an enlarged longitudinal section of the movable jaw shown in Figs. 1 and 2; and Fig. 5 is a cross-section of the adjusting rack-bar.

Similar numerals of reference refer to similar parts throughout the several views.

Two of the main objections to pipe wrenches as at present on the market, are, 35 that they do not firmly grip the pipe but often slip thereon as they contact therewith only at two opposite points as a rule, and that they often fly off the pipe and hit the operator under the strains applied thereto. 40 Another objection is found in the fact that the opening between the jaws is usually on one side, with the result that they cannot conveniently be used when there is but small working space around the pipe. In order 45 to overcome these objections I have devised the hereinafter described wrench.

The wrench consists of a fixed part, comprising a handle and a fixed jaw; a movable jaw adjustably pivoted to the fixed part; and a rack bar to hold the movable jaw in 50 position. The handle 1 is of suitable design and has a guide lug 2 extending to one side thereof, said lug or arm being slotted in its face to receive the end of the movable jaw 55 therein and in its sides to form the guide for the pivot of the said movable jaw. A

screw-bolt 3 passes transversely through the handle 1 and into the lug 2. A pivot pin 4 passes through the head of the bolt 3 and through the side slots 5 in the guide arm 2 and has a suitable nut and head thereon. A circular nut 6 is loosely mounted in a cavity 7 in the handle 1 and screws on the said bolt 3 to control the position of the head thereof in the arm 2 and therefore the position of the pivot pin 4.

A movable jaw 8, having its inner end reduced in size to pass through the face slot in the arm 2, is pivoted to the head of the screw 3 by the pivot pin 4, which passes through the end of the jaw. Since the pivot pin 4 can travel only in the slots 5 the inner end of the jaw 8 is adjustable only along the line of the said slots 5. The jaw 8 is free to turn about the pivot 4, in whatever position the said pivot may be placed in the slots 5, except as limited and controlled by the rack bar 9. This bar 9 is pivoted within a cavity in the fixed jaw 10, about half way between the end thereof and the screw 3, and extends 60 across the gap to the movable jaw. It is provided with teeth on both sides and may conveniently be made of a circular bolt having two opposite sides flattened as shown in Fig. 5. It passes through a cavity in the 65 jaw 8. A small tooth 11 is formed on the jaw 8 at the edge of the cavity therein and engages the teeth on the outer side of the rack 9. A transversely sliding latch 12 is mounted in the jaw 8 on the opposite side of 70 the cavity and has a tooth 13 which engages the teeth on the inner side of the rack 9. This latch 12 is pressed toward the rack 9 by a spring 14 and has a thumb knob 15 secured to it whereby the latch may be withdrawn from contact with the rack against the action of the spring 14 and thus the jaw 8 may be adjusted on the rack 9 to engage a 75 different point thereon.

The jaws 8 and 10 are hollow faced, and 80 are each formed with two surfaces at right angles to each other, the surfaces of the two jaws being complementary as shown in Fig. 1. The ends of the jaws are substantially in line with the roots thereof so that 85 when said jaws are brought close together the said ends will practically touch, and so that if the jaws are parallel the gripping surfaces are farther apart than the distance between the points of the jaws, so that 90 if an object is engaged by the gripping surfaces it cannot pass through the space be-

tween the ends until the said ends are further separated.

Suitable gripping pieces 16, preferably serrated, are loosely mounted in the jaws 8 and 10 by pins 17 which pass through holes 18 in the parts 19 of said pieces which enter into the hollowed portion of the said jaws, said holes being larger than the pins to permit of a limited motion of the pieces relatively to the jaws. Springs 20 press the pieces 16 toward the article to be gripped. The adjacent ends of the parts 19 of the pieces 16 engage each other as shown in Fig. 4.

15 In Fig. 3 the jaw 21 is similar to the jaw 8 in all points except that the shape of the gripping part is changed to provide for a single surface which is substantially parallel with the larger gripping surface of the fixed jaw 10.

20 It is evident that many variations of my device may be made, as for instance, the rack bar may be reversed and pivoted to the movable jaw and the latch may be mounted in the fixed jaw, without departing 25 from the spirit of my invention.

My wrench is operated in the following manner:—When it is to be applied to a pipe, the nut 6 is turned to approximately the 30 correct final position, in accordance with the size of the pipe to be gripped. Then the thumb knob 15 is drawn back and the jaw 8 is swung on the pivot pin 4, as in Fig. 2, until the ends are sufficiently separated to 35 allow them to pass over the diameter of the pipe. Then the jaw 8 is closed on the pipe (Fig. 1) as far as it is possible to force it, and the latch 12 is released thus locking it in position on the rack bar 9. At this time 40 it may be sufficiently tight to grip the pipe because the serrated pieces 16 engage it in four places and creep and shift under the strain (but cannot move far), but if it is necessary to tighten the grip further the 45 nut 6 is turned to force the pivot pin 4 farther out along the slots 5 thus bringing the jaws 8 and 10 closer together.

Having described my invention, what I 50 claim is:—

1. In a wrench, the combination with a

fixed portion having a handle formed on one end and a jaw formed on the other end; of a screw-bolt transversely mounted in the handle and slideable therein; a nut screwed on said screw-bolt and mounted in the handle whereby the position of said bolt is adjusted; a pivot pin mounted on the end of said screw-bolt; a movable portion pivoted to said fixed portion by said pin and having a jaw formed on its free end; and a rack 55 bar pivoted to one portion and adjustably engaging the other portion whereby the opening between said portions is adjusted.

2. In a wrench, the combination with a fixed portion having a handle formed on one end and a jaw formed on the other end; of an arm extending at right angles from said fixed portion between the handle and the jaw, and having a guide slot cut therein; a screw-bolt transversely mounted in the handle in line with the slot in the arm; a nut screwed on said screw-bolt and mounted in the handle whereby the position of said bolt is adjusted; a pivot pin mounted on the end of said screw-bolt and passing 70 through said slot and guided thereby; a movable portion pivoted to said fixed portion by said pin and having a jaw formed on its free end; and a rack bar pivoted to one portion and adjustably engaging the other portion whereby the opening between 75 said portions is adjusted.

3. In a wrench, the combination with a fixed portion having a handle formed on one end and a jaw formed on the other end; of a movable portion pivotally secured to the fixed portion and having a jaw formed on its free end; a rack bar pivoted to one portion and passing across the space between the two portions and having teeth 80 on two opposite faces thereof; means mounted on the other portion to engage the teeth of the rack; and a sliding latch mounted on said portion on the opposite side of said rack from said engaging means and 85 engaging the teeth of said rack.

FREDERICK M. LANDON.
